John B. Harding

United States Patent Office.

W. H. SAVOURNIN, OF PHILADELPHIA, PENNSYLVANIA.

Design No. 3,016, dated May 5, 1868.

DESIGN FOR A BOX.

The Schedule referred to in these Letters Patent and making part of the same.

TO ALL WHOM IT MAY CONCERN:

Be it known that I, W. H. SAVOURNIN, of Philadelphia, county of Philadelphia, State of Pennsylvania, have invented or produced a new and original Design for a Box; and I do hereby declare that the accompanying drawing, and the following explanation thereof, form a full, clear, and exact description of the said design.

In the accompanying drawing—

Figure 1 is a plan view of the box, and

Figure 2 a perspective view.

The box is rounded at one end, and has the inclined sides, *m m*, meeting at the point *x*. The interior of the box is separated by partitions into the circular compartment *a*, diamond-shaped compartment *b*, and the two angular compartments *c c*.

A box of the form illustrated and described, whether empty, or filled with toilet or other articles, is more ornamental and pleasing to the eye than compartment-boxes of the usual forms.

I claim the design for a box, substantially as described herein, and represented in and by the accompanying drawing.

In testimony whereof, I have signed my name to this specification in the presence of two subscribing witnesses.

W. H. SAVOURNIN.

Witnesses:

H. HOWSON,

WM. ALBERT STEEL.
